(57) **CLAIM**

The ornamental design for a touch sensor electric switch as shown and described.

DESCRIPTION

1. Touch sensor electric switch
1. Touch sensor electric switch
- 1.1 : Perspective
- 1.2 : Perspective
- 1.3 : Top
- 1.4 : Front
- 1.5 : Left
- 1.6 : Right
- 1.7 : Back
- 1.8 : Bottom
- 2.1 : Perspective
- 2.2 : Perspective

The broken lines in the drawings depict portions of the touch sensor electric switch that form no part of the claimed design. The touch sensor electric switch in design 1 is shown with a symbolic break in its length. The appearance of any portion of the article between the break lines forms no part of the claimed design.
